UNITED STATES PATENT OFFICE.

FREDERICK BRADMILLER, OF DAYTON, OHIO, ASSIGNOR TO THE SEYBOLD MACHINE COMPANY, OF DAYTON, OHIO, A CORPORATION OF OHIO.

PAPER-CUTTING MACHINE.

No. 918,120.

Specification of Letters Patent. Patented April 13, 1909.

Application filed June 5, 1908. Serial No. 436,856.

To all whom it may concern:

Be it known that I, FREDERICK BRADMILLER, a citizen of the United States, residing in Dayton, county of Montgomery, and State of Ohio, have invented certain new and useful Improvements in Paper-Cutting Machines, of which the following is a full, clear, and exact description, reference being had to the accompanying drawings, forming part of this specification.

The object of my invention is to provide a locking device for paper cutting machines, which shall positively stop and lock from movement, the operation of the clamp and cutting knife, in the event that for any reason the ordinary and usual power disconnecting devices should fail to operate.

In a paper cutting machine it is usual to provide an operating knife for throwing in the power to start the machine, and to arrange the construction so that at the end of each complete operation the driving power shall be disconnected.

It sometimes happens that the fly wheel or driving pulleys may for some reason fail to be disconnected, or the brakes which are usually employed to overcome the momentum of the machine after the power is disconnected, may for some reason slip and thus, by the momentum of the machine, the cutting knife may descend unexpectedly.

My invention, therefore, consists in the certain novel construction and arrangement of parts to be hereinafter particularly pointed out and claimed, in which a stop lever is provided so arranged in connection with the disconnecting devices that in the normal operation of the machine, the locking lever will be properly released. But in the event that for any reason the operation of the parts should continue under their momentum beyond the normal point of stoppage, the stop lever shall positively lock the parts and prevent movement thereof.

In the drawings Figure 1 is a front elevation of one side of a paper cutting machine, embodying my improvements. Fig. 2 is a side elevation of same. Fig. 3 is a rear elevation taken between the driving shaft and knife bar.

My invention is applicable to any of the well known types of automatic paper cutting machines, and I have selected for illustration such parts of a paper cutting machine as may be necessary to show the application of my

invention in the type of a paper cutting machine illustrated in the Patent No. 511972 of January 2, 1894, to Charles Seybold. 1 is one of the side standards of such paper cutting machine, 2 a portion of the reciprocating knife bar, 3 a portion of the knife driving plate, 4 one of the pulling bars connecting the driving plate with the knife bar at one end, and 5 the cutting table.

7 is the driving shaft provided with a fly wheel 8, and driving pulley 9, which parts are mounted loosely thereon, and for large size machines the driving shaft 7, is usually supported by a supplemental standard 10, outside the driving pulley.

In the operation of the machine, the driving plate 3, is reciprocated vertically in a diagonal direction so as to give a shearing cut to the knife, and 11 is one of the diagonal slots in the driving plate which is engaged by 75 a roller 12, on the standard, to guide the driving plate in this diagonal movement. The fly wheel and driving pulleys are coupled to the driving shaft 7, by a suitable friction clutch construction 13, which is thrown into 80 and out of operation by the arm 14, mounted on the shaft 15, journaled in suitable side supports, secured to the side standards. This shaft 15, carries the segment gear 16, which is engaged by the segment gear 17, 85 secured to the shaft 18, also journaled in suitable bearings on the side standard and parallel with the shaft 15. The shaft 18, carries on its outer end the operating lever 19, mounted in the head 20, on the end of the 90 shaft 18, so that the operating lever 19, can be turned on its longitudinal axis.

21 is a sleeve mounted by feather or spline on the shaft 18, so as to turn therewith, but adapted to slide lengthwise on the shaft 18, 95 and normally held in contact with the inner bearing of the shaft 18, by the coiled spring 22. The lower end of the operating lever 19, carries an arm 23, coupled by a link 24, with a stud on the sleeve 21. The sleeve 21 carries an arm 25, provided with an adjustable stud 26, which is engaged by a nose 27, on the driving bar 3, when the knife bar and driving bar are at the top of their throw. In this position the shafts 18 and 15 are rocked 100 so that the clutch mechanism for the driving shaft is disconnected.

In order to start the machine, it is necessary for the operator to first rotate the operating lever 19, on its longitudinal axis, 110

which movement by the link connection draws the sleeve 21, toward the operating shaft, and withdraws the stud 26, from contact with the end of the driving bar 3, and 5 the sleeve being held in this position, the operator can then rock the shaft 18, to throw the friction clutch and couple the driving pulley with the driving shaft. The machine being started, the operator releases the lever 10 19, the sleeve 21, is returned to its normal position, and upon the completion of the up stroke of the driving bar contact is made with the stud 26, and the shafts 18 and 15 are rocked to throw out the clutch mechanism 15 and disconnect the driving power. In order to insure against the momentum of the machine continuing the operation, after the driving power is disconnected, it is usual to provide a band brake on the driving shaft to 20 prevent this overthrow. It sometimes happens that these brakes may not operate successfully, either when freshly oiled or for other reasons, or the fly wheel and driving pulley may not disconnect from the driving 25 shaft, and in order therefore to positively lock the machine in the event of any such failure to stop upon the completion of the up stroke of the knife bar, I provide as follows: 28 is a stud mounted in the side frame, 30 and upon this stud is pivoted the lock lever 29, which lever extends down along the side of the standard to a point nearer the bottom in sliding contact with the side frame at the bottom at 30. This lever carries a lug 31, 35 preferably rectangular, which engages in a notch 32, cut in the end face of the driving bar 3. When the parts are in their normal position with the sleeve 21, carrying the arm 25, in its normal position, the lug 31 on the lock lever 29, is in engagement with the notch 32, on the driving bar, so that if for any reason the driving mechanism should fail to disconnect, or the brake fail to operate the lock lever 29, will securely lock the driving bar 3, to the frame, and the knife bar and clamp will be prevented from descending.

Some little clearance is left for the engagement of the lug 31, on the locking bar with the notch 32, on the driving bar, in order 50 that when the machine is stopped by the locking action of the lock bar, this bar may be released by backing up the machine, and space must be left to permit the driving bar to be raised slightly or otherwise the parts 55 could not be unlocked without great difficulty.

The arm 25, on the sleeve 21, carries a

bearing surface 33, which engages the side of the lock bar 29, so that whenever the machine is started in the usual way as above described, the arm 25, will contact with the lock lever 29, and withdraw the lug 31, from engagement with the notch on the driving bar, and during the descent of the driving bar, the lug 31, will have a sliding contact with the driving bar. At the end of the up stroke the lock lever will fall into locking position to lock the driving bar in the event of any overthrow.

Having thus described my invention what I claim as new and desire to secure by Letters Patent, is:

1. In a paper cutting machine, a starting lever, means to prevent actuation of the lever, mechanism for releasing the same, a 75 separate locking lever to lock the machine positively, and means for unlocking said lock lever upon the operation of the releasing mechanism.

2. In a paper cutting machine, in combination with the frame and a driving bar for the knife mechanism, of a starting lever, means to prevent actuation of the lever, mechanism for releasing the same, a separate lock lever pivoted to the frame and engaging the driving bar to lock the machine positively and means for unlocking said lock lever upon the 85 operation of the releasing mechanism.

3. In a paper cutting machine, in combination with the frame and a driving bar for the 90 knife mechanism, of a starting lever, means in the pathway of said driving bar to prevent operation of the starting lever, a separate lock lever pivoted to the frame and engaging said driving bar to lock the machine positively and means for releasing said lock lever and the starting lever simultaneously.

4. In a paper cutting machine, in combination with the frame and a driving bar for the knife mechanism, of a starting lever, rock 100 shaft operated thereby, sleeve feathered on said shaft carrying an arm in the pathway of said driving bar, a separate lock lever pivoted to the frame in contact with said arm and engaging said driving bar to positively lock 105 the machine and connecting mechanism intermediate said sleeve and starting lever, whereby the driving bar and the lock lever may be simultaneously released.

FREDERICK BRADMILLER.
